UNITED STATES PATENT OFFICE

164,824

CHANGE-OVER PRESSURE REGULATOR OR SIMILAR ARTICLE

Theodore A. St. Clair, South Euclid, Ohio, assignor to The Weatherhead Company, Cleveland, Ohio, a corporation of Ohio

Application December 22, 1950, Serial No. 13,546

Term of patent 14 years

(Cl. D78—1)

To all whom it may concern:

Be it known that I, Theodore A. St. Clair, a citizen of the United States, residing at South Euclid, Ohio, in the county of Cuyahoga and State of Ohio, have invented a new, original, and ornamental Design for a Change-Over Pressure Regulator or Similar Article, of which the following is a specification, reference being made to the accompanying drawing, forming a part hereof.

In the drawing:

Fig. 1 is a top plan view of a change-over pressure regulator embodying my new design;

Fig. 2 is a side elevation thereof;

Fig. 3 is a front elevation of the regulator; and, Fig. 4 is a rear elevation thereof.

Fig. 5 is a bottom view of the regulator as shown in Fig. 3, drawn on a somewhat reduced scale.

I claim:

The ornamental design for a change-over pressure regulator or similar article, as shown.

THEODORE A. ST. CLAIR.
